Elisha Waters, of Troy, N.Y.
Letters Patent No. 965 - Dated Nov. 17th 1857.

The schedule referred to in these Letters Patent and making part of the same.

To all whom it may concern:

Be it known that I, Elisha Waters, of the city of Troy, in the county of Rensselaer, and state of New York, have invented or produced a new and original Design for a Sliding-Drawer Match-Box, to be made of sheet metal or other material; and I do hereby declare, that the following is a full and exact description of the same, reference being had to the annexed perspective drawings making

Des. 965

2

a part of this specification, in which

Fig. 1 shows the box closed.

Fig. 2 partly open.

Fig. 3 the drawer of the Box; and

Fig. 4 the Case part.

The same letters refer to like parts in all the figures

My design consists in the particular external shape, or configuration of the box as herein described and represented in Fig. 1 of the annexed drawings: - the Box being oblong, with the opposite sides parallel and the adjacent ones at right angles to each other, and with the four corners, a.a, b.b, rounded; there being an oblong rectangular, sunken panel with rounded corners in the top, A, of the box, while the bottom of the box is flat, and a raised, rounded moulding, or head, along the two longest sides, one short side and the intermediate rounded corners, of the edge of the top of the Box. - the top edge of the other short side and of the other two rounded corners being square, the same as is the whole extent on the edge of the bottom of the box. - there being a slight abrupt widening of the box at the places where the two rounded corners a.a, meet the two longest sides of the box, all as shown in the annexed drawings. -

What I claim as my invention or production and desire to secure Extd by Letters Patent is the peculiar external shape or Configuration of the Box as herein S.M.P described and shown by the annexed drawings; and to such shape or configuration I confine my claim. -

Witnesses: -

John Moran.
